VEHICLE DOOR LATCH HANDLE STRUCTURE

Lake E. Clinker, Toledo, Ohio

Application December 5, 1936, Serial No. 114,408

3 Claims. (Cl. 70—208)

This invention relates to door latches for vehicles such as automobiles, but more particularly to door handle structures of the type in which the handle is adapted to be moved against the side of the door in a position substantially flush with the outer surface of the door and an object is to produce a sturdy and reliable handle structure of this character by which the handle in position of use is held against wobbling but which can be readily and conveniently forced inwardly against the side of the door either by a person on the outside of the door or by a person inside of the vehicle extending his hand out through the window to engage the handle.

Another object is to provide a door handle structure of the above character having the new and improved features of construction, arrangement and operation hereinafter described and for purposes of illustration but not of limitation, an embodiment of the invention is shown on the accompanying drawing in which

Figure 1 is a perspective view of a door latch unit showing the new and improved handle assembly connected thereto;

Fig. 2 is an enlarged vertical sectional elevation of a portion of an automobile door showing the handle structure mounted thereon;

Fig. 3 is an enlarged fragmentary sectional elevation of a portion of the handle structure showing the handle parts in their outward position or in position of use;

Fig. 4 is a composite perspective view of the dog and its actuating member which is adapted to hold the handle shaft in its inward position, and

Fig. 5 is a sectional view on the line 5—5 of Fig. 3, taken through the outer panel of the door showing the pocket or socket into which the handle is forced.

The illustrated embodiment of the invention comprises a door latch having a case plate 10 over which the bolt plate 11 is suitably guided, the bolt plate having the usual latch nose 12 which extends through an opening in the case

plate flange 13. A spiral spring 14 has one end fixed to the case plate 10 and its opposite end bears against the bolt plate 11, urging the latter into latching position. Rising from the bolt plate is an arm 15 which is engageable by the usual roll back 16 to enable the bolt to be retracted from the outside of the door as will be readily understood. Retraction of the bolt from the inside of the door is effected by remote control mechanism (not shown), connected to the outer end of the bolt plate. The above structure is well-known

to those skilled in this art and forms no part of the present invention.

The roll back 16 is secured by a pin 17 to a squared or non-circular shaft 18 which extends through a similarly shaped opening in the head 19 of a tubular handle shaft 20. In screw-threaded engagement with the outer end of the handle shaft is a handle 21 which is held against unscrewing by a screw 21^a. The handle 21 is adapted to be disposed in a socket 22 so that its outer surface is flush or substantially flush with the outer side of a door D as shown in Fig. 2. It will be apparent that when the handle is not in use, it will lie snugly in its socket 22 so that the door can not be readily broken into and also it is of advantage when the automobile is in motion since it removes a projecting part which has, in the past, caused many serious injuries. In this instance, the socket member 22 is a separate part, fitting into an opening in the outside panel of the door and is clamped in place by tongues 22^a which engage the inside of such panel and a flange 22^b on the outside thereof.

Formed on the outer end of the roll back shaft 18 is a collar 23 and interposed between the collar 23 and the handle 21 is a coil spring 24, which is compressed when the handle is in its inward or inoperative position and which urges the handle outward to the position shown by the dotted lines in Fig. 2 and by full lines in Fig. 3, when the handle shaft 20 is released.

The handle shaft 20 telescopes with and has bearing in a bearing sleeve 25 which is suitably secured to the door D to hold it in stationary position and an enlargement 26 is formed on the inner end of the bearing sleeve 25. Formed in the enlargement is a socket 27 to receive a dog 28 which is slidable radially in the enlargement 26. Formed on the inner end of the handle shaft 20 is an annular groove 29 into which the dog 28 is adapted to extend when the handle shaft is forced inwardly to its innermost position, thereby to hold the handle shaft in its inward or inoperative position. The inner end of the enlargement 26 is socketed to receive a hub 30 of the roll back 16 and the central portion of the roll back 16 on one side is socketed to receive the head 19 of the handle shaft 20. The head 19 is provided with an annular beveled surface 31 for a purpose which will hereinafter appear.

The dog 28 is formed with a T slot 31 to receive a T-shaped actuating member 32 on the stem of which is disposed a coil spring 33. The stem of the actuating member 32 extends outwardly from the socket 27 through a cover plate 34 and into

engagement with an operating slide 35, a nut 36 engages the outer end of the stem of the actuator 32 for retaining the same in position.

Spaced longitudinally from the enlargement 26 5 is an enlargement 37 of the bearing sleeve 25. The enlargement 37 is provided with diametrically opposed sockets 38 to receive balls 39 which are spring pressed by coil springs 40, the outer ends of which bear against screw caps 41. Normally or when the handle shaft 20 is in its inward position, the balls 40 engage in an annular groove 42 formed on the outer side of the shaft 20. When the dog 28 is released or moved away from the shaft 20 to allow the spring 24 to force the handle shaft outwardly, the outward movement is limited by the collar 23 which is engaged by the head 18 and when in that position, the balls 39 engage in the annular groove 29 as shown in Fig. 3. When in that position, it will be observed that the handle shaft 20 has a substantial bearing in the bearing sleeve 25, thereby preventing wabbling of the handle when in use. The spring pressed balls 39 assist in holding the handle shaft in its outward position and provide an anti-friction bearing for the shaft.

When it is desired, the handle can be readily pushed in towards the door D without any difficulty, the beveled surface 31 engages the dog 28 and cams it out of the way to allow the handle shaft to be pushed inwardly to its fullest extent and to the point that the dog 28 engages in the groove 29. In this position, the handle 21 is disposed within the socket member 22 substantially as shown in Fig. 2.

Release of the dog 28 can be readily effected from either side of the door. A finger 43 projects through a slot 44 in the inside of the door. The finger 43 forms a part of the slide 35 so that by lifting or pushing upwardly on the finger 43, the dog 28 will be lifted away from the handle shaft 20. Actuation of the dog from the outside of the door is effected by means of the key 45 which engages a cylinder lock 46 from which extends a spindle 47. The inner end of the spindle 45 extends into an opening 48 formed in the slide 35 and projecting from the inner end of the spindle 47 is a lug 49 which is adapted to engage one side or the other of the opening 48 to move the slide 35 in one direction or the other. In this manner, the slide 35 may be readily released by turning of the key 45 to lift the dog out of engagement with the handle shaft 20. The arrangement should be such that the key 45 can not be withdrawn from the lock 46 until the projection 55 49 is moved to such position that the dog 28 can be actuated by the spring 33 to operative position.

Numerous changes in details of construction, arrangement and operation may be effected without departing from the spirit of the invention, especially as defined in the appended claims.

What I claim is:

1. A handle structure for a vehicle door latch comprising a stationary bearing sleeve, an axially movable tubular handle shaft fitting said bearing sleeve, a handle on the outer end of said shaft, manually releasable means carried by said bearing sleeve for holding said handle shaft in its inward position, said releasable means compris-

ing a spring pressed dog and an annular groove in said handle shaft to receive said dog, a latch operating shaft fitting inside of said handle shaft, said operating shaft being rotatable with said handle shaft and enabling longitudinal movement of the handle shaft relative thereto, spring means urging the handle shaft outwardly of said bearing sleeve, spring pressed bearing elements carried by said bearing sleeve and engageable in said annular groove for holding said shaft in its outward position and being automatically releasable upon an inward push on the handle, and stop means for limiting the outward movement of said handle shaft at such point as to enable said handle shaft to have substantial bearing in said bearing sleeve, thereby to prevent wabbling of the handle when in use.

2. A handle structure for a vehicle door latch comprising a stationary bearing sleeve, an axially movable tubular handle shaft fitting said bearing sleeve, a handle on the outer end of said shaft, manually releasable means carried by said bearing sleeve for holding said handle shaft in its inward position, said releasable means comprising a spring pressed dog and an annular groove in said handle shaft to receive said dog, a latch operating shaft fitting inside of said handle shaft, said operating shaft being non-circular in cross section and fitting a similarly shaped opening in one end of said handle shaft, spring means urging the handle shaft outwardly of said bearing sleeve, spring pressed bearing elements carried by said bearing sleeve and engageable in said annular groove for holding said shaft in its outward position and being automatically releasable upon an inward push on the handle, stop means for limiting the outward movement of said handle shaft at such point as to enable said handle shaft to have substantial bearing in said bearing sleeve, thereby to prevent wabbling of the handle when in use, and means including a finger piece engageable from the inside of the door for lifting said dog out of dogging position.

3. A handle structure for a vehicle door latch comprising a stationary bearing sleeve, an axially movable tubular handle shaft fitting said bearing sleeve, a handle on the outer end of said shaft, manually releasable means carried by said bearing sleeve for holding said handle shaft in its inward position, said releasable means comprising a spring pressed dog and an annular groove in said handle shaft to receive said dog, a latch operating shaft being non-circular in cross section and fitting a similarly shaped opening in one end of said handle shaft, spring means urging the handle shaft outwardly of said bearing sleeve, spring pressed bearing elements carried by said bearing sleeve and engageable in said annular groove for holding said shaft in its outward position and being automatically releasable upon an inward push on the handle, stop means for limiting the outward movement of said handle shaft at such point as to enable said handle shaft to have substantial bearing in said bearing sleeve, thereby to prevent wabbling of the handle when in use, and a slide for releasing said dog from dogging position.

LAKE E. CLINKER.
